UNITED STATES PATENT OFFICE.

CHARLES W. LOGAN, OF KENMORE, NEW YORK, ASSIGNOR TO MARKEL ELECTRIC PRODUCTS, INC., OF BUFFALO, NEW YORK, A CORPORATION OF NEW YORK.

DESIGN FOR AN ELECTRIC-LIGHT CEILING FIXTURE.

Application filed May 14, 1929. Serial No. 31,217. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for an Electric-Light Ceiling Fixture, of which the following is a specification, reference being had to the accompanying drawing, forming part thereof.

In said drawing:

Figure 1 is a side elevation of an electric light ceiling fixture embodying my new design, one half of the fixture being shown in

full lines while the marginal outline of the remaining half which repeats the design, is indicated by dot and dash lines.

Figure 2 is a bottom plan view of the same, a quarter sector of the fixture being shown in full lines while the marginal outline of the other sectors, all of which repeat the design, are indicated in dot and dash lines.

I claim:

The ornamental design for an electric light ceiling fixture, substantially as shown and described.

CHARLES W. LOGAN.
